UNITED STATES PATENT OFFICE.

FRED HOWLAND, OF NOGALES, ARIZONA.

LIQUID AND GASEOUS FUEL BURNER.

1,384,955.

Specification of Letters Patent. Patented July 19, 1921.

Application filed December 30, 1919. Serial No. 348,281.

To all whom it may concern:

Be it known that I, FRED HOWLAND, a citizen of the United States, residing at Nogales, county of Santa Cruz, and State 5 of Arizona, have invented a new and useful Improvement in Liquid and Gaseous Fuel Burners, of which the following is a specification.

My present invention relates to improvements in liquid and gaseous fuel burners 10 that are structurally designed to adapt them to coal burning or other stove structures, either of the heating or cooking type, and the invention involves a burner of the type 15 which has an underlying retort in the form of separated and independent chambers beneath the burner nozzle or nozzles wherein the fuel is heated or vaporized before passing to the nozzle, the heating and vaporization being accomplished by directing the 20 flame in contact with the retort.

The primary object of the invention is the provision of a device of this character, made up in units and each unit comprising an integral, one-piece metallic casting, compactly 25 arranged and of neat design, of simple and substantial construction to withstand the action of heat while performing its functions and to render it facile in operation 30 and comparatively inexpensive in cost of production and operation. By the utilization of my invention I am enabled to supply a device of this character that may with facility be applied to any stove or furnace 35 constructions without necessity for changing the structure of the fuel burning stove or furnace and without requirement of special tools or expert labor, and the device may, with equal convenience and despatch be used 40 dissociated from such structure if required.

To this end the invention consists in an integral casting involving a reservoir or retort preferably formed with two vaporizing or heating chambers for the fuel and a 45 single piece tubular member integral with the retort fashioned as gas pipes communicating with these chambers and provided with burner nozzles or nozzle openings for the jet or flame, and the invention further 50 consists in certain novel combinations and arrangements of parts as will be hereinafter more fully pointed out and disclosed in the drawings.

In the drawings I have illustrated one 55 complete example of the physical embodiment of my invention, the parts being con-

structed and arranged according to the best mode I have so far devised for the practical application of the principles of my invention, but it will be understood that I contemplate changes and alterations therein, within the scope of my claims without departing from the spirit of the invention.

Figure 1 is a side elevation, partly in section, of the fuel burner, detached, embodying the present invention.

Fig. 2 is a top plan view of the burner.

Fig. 3 is an end view, seen from the left in Fig. 1.

Fig. 4 is a vertical transverse sectional view on line 4-4 of Fig. 1.

In the preferred form of the invention as illustrated in the drawings, the single unitary casting, of suitable metal, embodies the retort 1 which is longitudinally divided 75 into two heating chambers 2 and 3, a transverse, integral, partition 4, centrally located in the retort being provided to form these separated, non-communicating chambers. Preferably the lower portion of the retort is 80 rounded to convenient form, but the upper or top plate 5 of the retort, which is the firing plate, is specially constructed flat with a plane surface and of required thickness and width, and extends the length of 85 the retort to receive the heated currents or flame from the burner.

The non-communicating gas chambers are bounded at their ends by the intermediate partition and the two end walls 6 of the retort, and interiorly threaded bosses 7 are provided in the walls of the chambers to receive the fuel pipes 8, a control and regulating valve 9 being supplied to regulate the passage of liquid fuel from the tank (not 90 shown) to the retort. The tank is located as usual in a higher plane than the burner in order that the fuel may be supplied by gravity, and the desired feed of gasoline or liquid fuel to the retort is governed by the 95 valves in customary manner, the valves of course being located outside the stove and readily accessible to the attendant.

In casting the device an integral tubular extension, communicating with the gas 105 chambers is provided, and fashioned as vertical gas pipe 10 and 11, joined by the horizontal portion 12 lying parallel with and above the retort and spaced therefrom at a predetermined and suitable distance. 110 The vertical gas pipes each communicates with a gas chamber, and the bent ends of the

pipes, an integral member, are separated by a transverse, interior, partition 13, alined with the intermediate partition 4 in the retort, thus providing each chamber with an outlet pipe with its discharge portion overlying and parallel with the retort, or with its complementary gas chamber.

The respective discharge pipes are provided with a nozzle or jet openings 14, 15, 10 directing the flame as indicated by the arrows to the firing plate 5 of the retort, and it will readily be apparent that the gas passes from the chambers, through the gas pipes, and thence through the nozzle openings, where it is ignited and directed downwardly in a flame which reaches the firing plate and is then deflected and curled upwardly in usual manner.

In the process of casting the burner a sand core is employed which may be withdrawn through openings which are afterward closed by plugs 16 in the horizontal portion 12 of the extension, and this manner of constructing the single unitary structure insures 25 against a "blow up" of the casting, and results in a smooth interior finish for the retort and its extension, and as there are no separable parts to the structure, disconnection of members is eliminated, and the durability of the burner is enhanced.

Variations may be made in the size of the burner to suit different purposes, and differing numbers of units may be employed in alinement in the fire box of the structure 35 to achieve desired results within wide limits, and it will readily be apparent that the pipes 8 may be passed through the draft openings of a stove to the burner that is located in the fire box, thus adapting the 40 burner to existing stoves or structures without modifying or altering the stoves or structure in any manner, as indicated by dotted lines in Fig. 2.

One of the burner nozzles may be employed if desired when only a moderate heat 45 is required, and the other may of course be utilized to increase the heat, and the use of additional units may be employed to secure further increased heat.

In starting the fire the retort may be 50 heated by burning inflammable material, as paper, thereon to heat and vaporize a sufficient quantity of the liquid fuel to be ignited, using a small amount of liquid fuel, if desired, to assist in the combustion of the 55 paper, and then the valve may be opened to supply from the nozzle opening a continuous stream of gas which is ignited. The blue and white flame thus fills the firebox of the structure, continuously heating the retort through the firing plate thus vaporizing the liquid fuel, as readily understood.

Having thus fully described my invention, what I claim is:

1. The combination in a gaseous fuel 65 burner with a retort fashioned with a plurality of heating chambers and a fuel supply pipe for each chamber, of a closed tubular extension forming a pair of gas pipes 70 communicating with said chambers, said extension having a horizontal portion forming non-communicating gas-pipe ends and provided with nozzle openings to direct flame to the retort.

2. A single piece, cast fuel burner comprising 75 a retort fashioned with a transverse interior partition forming separated chambers and upright, integral gas pipes rising from said retort and communicating with the chambers; an integral horizontal pipe 80 section parallel with the retort and joining said gas pipes; an integral transverse partition in the horizontal section, there being nozzle openings in said horizontal section at the sides of the partition, and fuel supply 85 pipes to said chambers.

3. The combination with a retort having a flat flame plate and interior transverse partition forming separated chambers beneath said plate, gas pipes rising from said 90 plate each communicating with a chamber, a horizontal pipe section joining said gas pipes and provided with nozzle openings, a transverse partition in said pipe section between said openings and fuel supply pipes 95 to said chambers.

FRED HOWLAND.
